UNITED STATES PATENT OFFICE.

EDWARD B. NICHOLSON, OF OSHKOSH, WISCONSIN, ASSIGNOR TO H. A. HYATT, OF ST. LOUIS, MISSOURI.

PHOTOGRAPH-CUTTER.

SPECIFICATION forming part of Letters Patent No. 659,983, dated October 16, 1900.

Application filed March 2, 1900. Serial No. 7,118. (No model.)

To all whom it may concern:

Be it known that I, EDWARD B. NICHOLSON, a citizen of the United States, residing at Oshkosh, in the county of Winnebago and State of

5 Wisconsin, have invented new and useful Improvements in Photograph Gages and Cutters, of which the following is a specification.

10 My invention relates to an apparatus for cutting both the mask that is used in printing the photograph and the photograph after it is printed.

In dark-colored mountings it is desirable to have a narrow white interspace between the photograph and the mounting.

15 The objects of my invention are, first, to make a white border around the printed photograph which will show as an interspace between the photograph and mat when mounted; second, to simplify and cheapen the cost of 20 so doing, and, third, to insure absolute uniformity in the width of the border.

I am aware that photograph-cutters have heretofore been constructed and used consisting of a roller-cutter which was adapted to be 25 moved around the edge of a guide-pattern to cut the photograph in an oval or circular form. Two guide-patterns could be used, one slightly smaller than the other, to cut the mask, so that in laying it between the negative and 30 printing-paper in printing it would preserve a white margin which would not be exposed to the sun's action. In the use of two guide-patterns, however, uniformity in width of the white border or margin could not be obtained, 35 as the edges of the patterns soon wear away so as to destroy their conformity to each other, and the patterns were expensive to manufacture. In my invention I provide a means of cutting both the mask and the photograph by 40 the same guide-pattern.

In the accompanying drawings, Figure 1 is a front view, and Fig. 2 a side view, of the cutter. Fig. 3 represents a circular guide-pattern. Fig. 4 shows the mask and bed-plate, and Fig. 5 a photograph mounted.

45 Similar letters refer to similar parts in each view.

A represents the handle, B the swivel-joint, and C the cutting-wheel, pivoted to the ears 50 D D.

c represents the cutting edge of the wheel C, and c' the opposite side.

E is a bed-plate, of glass or analogous material.

F is a circular pattern, H the photograph, 55 and I the mount.

It will be observed that the cutting edge c is without the center of the periphery of the wheel C.

In operating my invention the cutting-wheel is passed around the edge of the pattern F, the side of the wheel C in its revolution bearing against the edge of the pattern. The wheel is at the same time pressed downward upon the bed-plate E, cutting the interposed mask or sensitized paper as it is passed along. When cutting the mask, the side c' of the wheel C is permitted to bear against the edge of the pattern, thus bringing the cutting edge c a slight distance away from 70 the pattern edge. The mask is thereby made slightly smaller than the pattern. Then in cutting the photograph after printing the cutting-wheel is reversed, the swivel B permitting of such rotation, and the cutting-edge 75 c is permitted to bear against the pattern edge in its rotation. The photograph is thereby made slightly larger than the mask. The mask is first made, then placed between the negative and printing-paper within the printing-frame, and the margin around the photograph, being covered by the mask, remains unprinted and of a white color. After printing the photograph is removed, trimmed by means of the cutting-wheel, as hereinbefore 80 described, pasted to the dark mount I, and the white margin J has the appearance of an interspace between the photograph and the mounting.

Having thus described my invention, what 90 I claim, and desire to secure by Letters Patent, is—

1. A photograph-cutter comprising a swiveled shank having bifurcated jaws at its lower end, a cutting-wheel mounted between the 95 said jaws and having its cutting edge arranged to one side of the center, whereby the cutter will more easily follow the edge of a pattern, a draw-handle carrying the swiveled shank, said handle extending to one side 100

thereof, whereby the cutter can be readily drawn along the guiding edge of a pattern, substantially as described.

2. A cutter for cutting irregular figures or openings, comprising a vertical shank having an enlarged lower end bifurcated at the bottom, a rotary cutter pivotally mounted in the bifurcated portion and having its cutting edge arranged to one side of the center, a reduced portion upon the shank, a handle having projecting lugs for engaging the said reduced shank, means for loosely holding the shank in place, the said handle extending to one side

of the shank, whereby sufficient pressure can be brought to bear upon the cutter, the mounting of the cutter being such that it will readily follow the pattern in cutting figures or apertures.

In testimony whereof I have hereunto set my hand in the presence of two subscribing witnesses.

EDWARD B. NICHOLSON.
